UNITED STATES PATENT OFFICE.

EDWARD A. ROCKWELL, OF NEW YORK, N. Y., ASSIGNOR, BY MESNE ASSIGNMENTS,
TO STEWART-WARNER SPEEDOMETER CORPORATION, A CORPORATION OF VIR-
GINIA.

MEANS FOR SUPPORTING VACUUM FEEDING SYSTEMS.

Application filed June 4, 1919. Serial No. 301,825.

To all whom it may concern:

Be it known that I, EDWARD A. ROCKWELL, a citizen of the United States, residing at New York city, in the county of New York and State of New York, have invented a certain new and useful Improvement in Means for Supporting Vacuum Feeding Systems, of which the following is a specification.

My invention has reference to an apparatus designed for feeding liquids of various kinds, but has special reference to apparatus designed for feeding liquid fuel to automobile engines.

The object of my invention is to provide an apparatus by means of which liquids of various kinds may be fed, but which is especially adapted for feeding fuels to internal combustion engines, the same being effectively held in place, as for example upon an automobile, by an especially advantageous clamping means for securing the same in the desired position.

Further objects of my invention will appear from the detailed description thereof contained hereinafter.

While my invention is capable of embodiment in many different forms, for the purpose of illustration I have shown only one form of my invention in the accompanying drawings, in which;

Figure 1 is a vertical section of an apparatus made in accordance with my invention, and

Figure 2 is a plan view partly in section of the vacuum chamber of an auxiliary supply tank.

In the drawings, I have shown a vacuum chamber 1, which is connected by means of a pipe 2 to a main supply tank for fuel, such as gasoline, and which is connected also by a pipe 3, having a small port 4, to the intake manifold of an internal combustion engine, such for example as an automobile engine. At the top of the chamber 1, which, as shown, is of restricted diameter in comparison with a supply tank 9, there is, furthermore, provided a valve casing 5, which carries therein a vacuum release valve 6. A cover 7 prevents the entry of dirt into the valve casing 5. The lower free edge of the chamber 1 has a shouldered flange 8 which fits over the top of the auxiliary supply tank 9, and is shown as secured thereto by means of screws 10. Said auxiliary supply tank 9 has a bottom closure 11 which is connected

by a pipe 12 to the carburetor of the internal combustion engine above referred to. A vent pipe 13 extends upwardly from the top of the tank 9 through the chamber 1, and out through the top of the latter through a socket 14. The exterior of the socket 14 is screwthreaded to receive an hexagonal cover 15 which has a circular cap 16 secured to the top of the cover 15, so as to allow spaces 17 at intervals around the cap 16 through which air may pass. The chamber 1 and the associated tank 9 are supported by means of a bracket 18 whose basal portion is shown as surrounding the lower portion or base of the tank 9. The bracket 18 has an upwardly-directed tongue 19, which may be spot welded thereto, said bracket being preferably adapted to be secured by means such as screws 20 to the dash board or any other part of an automobile. Spot welded or otherwise secured to the top of the tongue 19 there is shown a metal strap 21, which, in the form shown, is of less circumference than is the basal portion of the bracket, and which has at one end thereof a hook 22 for engagement with a yoke 23, shown as connected by a square ring 24 to a loop 25 on the other end of the strap 21. It will be, of course, understood that any desired type of vacuum apparatus may be carried by this supporting device.

In the operation of my apparatus, it will be understood that the vacuum feeding system will supply in any desired manner liquid fuel from the main supply tank to the carburetor by the action of the vacuum produced by the engine which is driven by the fuel thus supplied to the carburetor. The vacuum apparatus is securely held in place at all times by the supporting means, but in such a manner as to be removable when desired. Whenever it is desired to repair the apparatus in any manner, it can readily be removed by disengaging the yoke 23 from the hook 22, bending the ends of the strap 21 apart, and disconnecting the pipes 2, 3 and 12 from the chamber 1 and the tank 9.

While I have described my invention above in detail, I wish it to be understood that many changes may be made therein without departing from the spirit thereof.

I claim:

1. In combination, a bracket having a vertical portion with means for securing it to

- a support, a single supporting flange at the bottom of the bracket extending outwardly therefrom so that a container may be laterally placed thereon, a clamping means attached to the upper end of the bracket, and a hook and loop at the respective ends of the clamping means with a ring connected to the loop, and a yoke fastening the ring and hook in operative engagement.
- 10 2. In combination, a bracket having a vertical portion with means for securing it to a support and an upper portion bent away from the vertical portion and support, a single supporting flange or ledge at the bottom of the bracket extending outwardly therefrom so that a container may be laterally placed thereon, and circular clamping means attached to the said upper portion of the bracket having a smaller diameter than said container, and having a fastening
- 15 3. In combination, a bracket having a vertical portion with means for securing it to a support, a single supporting flange or ledge at the bottom of the bracket extending outwardly therefrom so that a container may be laterally placed thereon, a circular clamping means attached to the upper end of the bracket said circular means having a 25 smaller diameter than the diameter of said container, and a hook and loop at the respective ends of the clamping means with a ring connected to the loop and a yoke fastening the ring and hook in operative engagement.
- 30 In testimony that I claim the foregoing, I have hereunto set my hand this 23rd day of May, 1919.

EDWARD A. ROCKWELL.
